UNITED STATES PATENT OFFICE.

HERBERT G. STONE, OF WYTHEVILLE, VIRGINIA.

PROCESS OF RECOVERING ACID.

1,314,765.

Specification of Letters Patent. Patented Sept. 2, 1919.

Application filed June 4, 1919. Serial No. 301,601.

To all whom it may concern:

Be it known that I, HERBERT G. STONE, a citizen of the United States, residing at Wytheville, in the county of Wythe and State of Virginia, have invented certain new and useful Improvements in Processes of Recovering Acid, of which the following is a specification.

This invention relates to processes of recovering acid; and it comprises a method of recovering acetic acid from vapors of tanning extracts undergoing concentration in multiple effect apparatus, as well as of recovering other volatile acids from other liquids, wherein such vapors are passed through a casing without material impairment of their heat or velocity and while in such casing are contacted with sprayed alkali solution; and it further comprises as a new organization of apparatus elements a pair of multiple effect evaporators with a special casing located in the vapor line between the two, such casing being provided with spraying means for alkali; all as more fully hereinafter set forth and as claimed.

Ordinary commercial tanning extracts are made by leaching or extracting various woods and barks in well known ways, and afterward evaporating down the watery solutions so obtained to a convenient commercial density, or even to dryness. In evaporating, for the sake of economy of fuel and to avoid damaging the materials by high heat, it is usual to employ what are known as multiple effect evaporators, evaporators working under vacuum and so connected that the vapors of one are used in the heating coils or heating elements of another to produce evaporation therein; the second one, of course, always operating under lower pressure than the one in which the vapors originated.

In all extracts, or practically all, of vegetable materials of the nature of woods and barks there is found a small amount of free acetic acid. Its amount is rarely great but there is usually some. In evaporating these extracts, because of the peculiar relations of acetic acid to water in distillation, acetic acid occurs in the vapors throughout the concentration. The concentration in any given extract is not over one-tenth per cent. or so, although at times it is higher, but in the aggregate in an ordinary factory this small percentage of acid in the liquor means a considerable amount in the course of a

day. The amount is worth recovering and, furthermore, the presence of acid in the vapors renders the vapors and condensates more or less corrosive. For this reason also it is worth while removing the acid from these vapors. In so removing the acid, the usual types of neutralizing apparatus are impracticable as applied to dealing with vapors between effects, for the reason that it is not practicable to cool such vapors to any substantial extent or to cut down their velocity of travel. It would naturally be inexpedient in running two connected pans, the vapors from the one heating the other, to place any substantial impediment in the path of the vapors between the two.

I have however found that I can recover the acetic acid from the vapors of evaporation by the use of several expedients without in any way impairing the capacity or operation of the evaporators. To this end I place in the vapor line a casing of sufficiently great cross section to afford not only free passage of vapors, but slow down temporarily their passage somewhat without placing friction in the line. Within this casing, I mount means for spraying alkali; this means being connected to suitable pumping means so that the liquor deposited in the bottom of the casing, after being sprayed may be sent back to the spraying means. In recovering acetic acid from bark extracts I customarily use lime as the alkali, producing calcium acetate. Soda may be used for neutralizing but is open to the objection that more or less tanning material usually passes forward with the vapors by entrainment and soda forms soluble compounds with the tannins. By using lime in the manner described, that is, with a cyclic circulation to and through the neutralizing casing and spray nozzle therein, I obtain a calcium acetate solution of high grade; the salts produced from it by further evaporation frequently analyzing as high as 99 per cent. calcium acetate. It is a much higher grade preparation than the usual crude acetate from the wood distilling plants; being white or reddish white in appearance and susceptible of solution, evaporation and reconcentration to give a chemically pure acetate. Because of the circumstances within the neutralizing casing, the solution may be withdrawn in a saturated condition or of a less concentration as may be desired. In operating under the present process a charge of

alkali may be placed in the system and circulated and recirculated until it is converted into a neutral acetate solution; or there may be a continuous feed of alkali to the circulating system and a continuous withdrawal of neutral acetate.

While I have more particularly described the present invention with reference to its application to the recovery of acetic acid from evaporated tanning extracts, it may of course be applied to other evaporation where, for one reason or another, it is desirable to remove acid from vapors between effects, as in evaporating sulfite waste liquors.

In the accompanying illustration I have shown, more or less diagrammatically, certain apparatus within the present invention and useful in the performance of the described process. In this showing the view is a central vertical section, certain parts being in elevation. In this showing elements 1 and 2 are fragmentally shown multiple effect pans of any usual construction provided with vapor connections 3 and 4 respectively. As shown, these are represented as the first and second effects (in order of decreasing temperature) of a multiple effect assemblage. Between the two effects and receiving vapor from the vapor outlet from the first is an acid catcher indicated as a whole by 5. As shown, entering vapors pass through conduit 6 into a somewhat expanded spraying chamber 7, having a perforated spray plate 8 mounted therein. Below this expansion is downtime 9, shown as ending immediately above a series of stationary vanes 10, mounted on spider 11. These vanes serve to give a whirling motion to the mixture of vapors and liquid (acid solution). As shown the casing is of considerably greater diameter than the vapor line proper, to provide for a certain amount of slowing up of vapors passing therethrough. At the top the casing is connected to vapor line 12, leading to the inlet for heating vapors of the next effect. Mounted on this vapor line is a catch-all 13 with conduit 14 leading liquid back to the acid casing. At the bottom of the acid casing is a valved liquid outlet 15 connected to centrifugal pump 16. Entering this line is a valved

alkali inlet 17. From the centrifugal pump on the pressure side conduit 18 leads back into the casing, terminating in an upwardly directed spray nozzle 19. This conduit is valved at 20 and is provided with valved outlet 21 for acetate solution.

In the use of this apparatus, the vapors entering pass into the expanded chamber 60 in line 6 where they are met by a spray containing lime. This finely divided spray causes intimate contact of the alkali with the vapors and effectually removes acids from the vapor without condensation of the 65 vapor. The drops of liquid coming from the spray nozzle pass downward through the perforated plate and thence downward to the bottom of the casing for removal by the pump. Vanes 10 give a whirling motion to the vapor, throwing any entrained drops of liquid to the periphery of the casing. The steam coil 22 serves to maintain temperature in event there is too much cooling effect due to expansion of the vapors. 75

What I claim is:

1. The process of recovering acetic acid from the vapors of vegetable extracts undergoing evaporation in multiple effect apparatus which comprises intimately contacting 80 alkali with the vapors passing from effect to effect.

2. The process of recovering acetic acid from the vapors of vegetable extracts undergoing evaporation in multiple effect apparatus which comprises spraying lime into the vapors passing from effect to effect. 85

3. In the operation of multiple effect evaporators, the process which comprises spraying alkali into the vapors passing between effects. 90

4. The combination with multiple effect apparatus of vapor treating apparatus located between the inlet of one effect and the outlet of another and adapted to receive the 95 vapors from one effect and deliver them to the other, such casing provided with means for spraying the said vapors with treating material while the vapors are passing from one effect to another. 100

In testimony whereof, I affix my signature hereto.

HERBERT G. STONE.
